UNITED STATES PATENT OFFICE.

HOWARD M. BARBER, OF STONINGTON, CONNECTICUT, ASSIGNOR TO C. B. COTTRELL & SONS COMPANY, OF STONINGTON, CONNECTICUT, A CORPORATION OF DELAWARE.

MEANS FOR APPLYING ANTOFFSET MATERIAL TO THE FRESHLY-PRINTED SIDES OF TRAVELING WEBS.

Application filed January 31, 1924. Serial No. 689,686.

To all whom it may concern:

Be it known that I, HOWARD M. BARBER, a citizen of the United States, and resident of Stonington, in the county of New London and State of Connecticut, have invented a new and useful Improvement in Means for Applying Antioffset Material to the Freshly-Printed Sides of Traveling Webs, of which the following is a specification.

10 In printing presses where slip sheets have been used for separating the printed sheets in the pile to prevent offsetting and smutting, the printed sheets have been delivered from the press with their freshly printed sides up. It has been heretofore attempted to do away with the use of the slip sheets by applying anti-offset material to the freshly printed side of the web or sheet. To produce the best results the anti-offset material 15 when in liquid form must be deposited in a very thin and uniform film upon the freshly printed side of the web or sheet, for, if the anti-offset liquid is permitted to accumulate and drop onto said web or sheet, 20 it will not only discolor the web or sheet but will cause the sheets to stick together, when stacked in a pile, because of the character of the anti-offset liquid used for this purpose.

25 My present invention is directed to means for so printing the web that it may be readily led off from the printing mechanism with its freshly printed side down, and so locating the anti-offset supply device under 30 the web that the anti-offset material will be directed upwardly against the freshly printed side of the web; any excess material which might accumulate in quantities sufficient to form drops, being caused to drop 35 away from instead of onto the web; the object being to provide means whereby the best class of color printing may be produced and the sheets stacked in piles without the use of interposed slip sheets or the danger 40 of offsetting or smutting.

45 A practical embodiment of my invention is represented in the accompanying drawing which represents in diagram a multi-color rotary web perfecting printing press with 50 my improvements applied thereto.

The printing mechanism for printing on one side of the web 1 is herein shown as arranged to print in two colors thereon, the

impression cylinder being denoted by 2, the two form cylinders by 3 and 4 and their 55 respective groups of inking rollers by 5 and 6.

The printing mechanism for printing upon the opposite side of the web 1 is herein shown as arranged to print in four colors 60 thereon, and comprises the impression cylinder 7, the four form cylinders 8, 9, 10, 11 and their respective groups of inking rollers 12, 13, 14 and 15. These form cylinders are located around the underside of the impression cylinder 7 so as to permit ready leading off of the web from the impression cylinder with the last freshly printed side down.

An offset web 16 leads from the supply 70 roll 17, around the impression cylinder 7, to the winding roll 18 to take care of the first freshly printed side of the web.

The means which I have shown for applying the anti-offset material to the last freshly printed side of the web 1 is herein shown as comprising a reservoir 19 for a liquid anti-offset material, said reservoir being located under the web and being provided with atomizing nozzles 20, 21, the nozzle 21 being 80 in communication with a source of pressure, (not shown herein) through a supply pipe 22. Thus the anti-offset liquid will be sprayed upwardly onto the last freshly printed side of the web in a thin even film 85 as it is led off from the impression cylinder 7; any accumulation of liquid at the nozzle or any excess supply being allowed to drop away from the web instead of onto the web, thus preventing any liability of the web 90 becoming injured by such excess anti-offset liquid being dropped thereon.

It is obvious that the anti-offset applying device may be used in connection with the printing of webs either in one or more colors 95 on one or both sides of the web, without departing from the spirit and scope of my invention, the object being to lead off the web with its freshly printed side down and to direct an anti-offset material upwardly into 100 contact with said freshly printed side of the web.

What I claim is:—

1. In a rotary web printing press, means for printing on the traveling web, means for 105 leading off the web with the freshly printed

- side down, and a device located under said web for spraying an anti-offset liquid upwardly against the freshly printed side of the web.
5. 2. In a rotary web perfecting printing press, means for printing successively upon both sides of the traveling web, means for leading off the web with the last freshly printed side down, and a device located under said web for spraying an anti-offset liquid upwardly against the last freshly printed side of the web.
10. 3. In a multi-color rotary web perfecting printing press, means for printing in multi-color upon one side of the traveling web, means for printing in multi-color upon the other side of the traveling web, comprising an impression cylinder and its coating form cylinders located around the under side of the impression cylinder, means for leading off the web with the last freshly printed side down, and a device located under said web for spraying an anti-offset liquid upwardly against the freshly printed side of the web.
15. 4. In a multi-color rotary printing press, means for printing in multi-color on one side of the traveling web, comprising an impression cylinder and its coating form cylinders located around the under side of the impression cylinder, means for leading off the web with the freshly printed side down, and means for spraying an anti-offset liquid upwardly against the freshly printed side of the web.
20. 5. In a multi-color rotary printing press, means for printing in multi-color on one side of the traveling web, comprising an impression cylinder and its coating form cylinders located around the under side of the impression cylinder, means for leading off the web with the freshly printed side down, and a device located under said web for spraying an anti-offset liquid upwardly against the freshly printed side of the web.

In testimony, that I claim the foregoing as my invention, I have signed my name this 29th day of January 1924.

HOWARD M. BARBER.
